UNITED STATES PATENT OFFICE

STEPHEN L. WILLIAMS, OF BRIDGEPORT, OHIO, ASSIGNOR TO EXTRUDED METAL PRODUCTS COMPANY, OF BRIDGEPORT, OHIO, A CORPORATION OF OHIO

PICKLING APPARATUS

Application filed June 19, 1929. Serial No. 372,158.

This invention relates broadly to pickling apparatus, and more particularly to an apparatus for pickling metal tubing, bars, and the like.

5 The primary object of the invention is to provide a pickling apparatus which has novel and improved means of a simplified nature for moving the material to be pickled into and out of the pickling fluid of the bath.

10 A further object of the invention is to provide an apparatus of this type which effects drainage of the pickling fluid from the material.

A still further object of the invention is to 15 provide a pickling apparatus of the character mentioned in which the positions occupied by the tubes being pickled are changed with respect to each other with each reciprocation into the pickling bath, thereby permitting access of the pickling fluid to the entire surface of the tubes or other material being pickled.

In describing the invention in detail, reference is herein had to the accompanying 20 drawings, in which—

Figure 1 is a top plan view of the invention;

Figure 2 is a side elevation partly broken away; and—

30 Figure 3 is a section on line 3—3, Fig. 1.

In proceeding in accordance with the present invention a pair of companion pickling tanks 1 are employed for containing the pickling bath. These tanks are of rectangular 35 form and are arranged in spaced side by side parallel relation. On the outer side of each of the tanks is located a plurality of vertical columns 2, similar columns 3 being disposed in the space between the tanks, and all of 40 said columns being in register in planes transversely of the lengths of the tanks.

Referring particularly to Figures 1 and 3 of the drawings, it will be noted that there is provided a series of chains 4 which extend 45 transversely of the tanks, the ends of the chains being secured to the brackets 10, said brackets being mounted upon or secured to the upper ends of the columns 2, while the central portions of the chains engage over 50 gear wheels 5 carried by a longitudinal shaft

6, the shaft 6 being journaled in bearings 7 mounted upon the upper ends of the central columns 3.

It will be noted that the chains are of such length that they form a pair of loops 4^a, one of such loops being disposed directly over each tank. Threaded adjusting devices 8 connect the ends of the chains to the brackets 10 and provide means whereby said chains may be lengthened or shortened as desired. 55

Referring to Fig. 2 of the drawings, it will be noted that the material to be pickled, shown as tubes or bars, are held by the chains in the pickling tanks at an incline to the horizontal, thereby facilitating drainage of the pickling fluid. In order to effect this manner of supporting the material at an incline, the chains have a stepped relation. Otherwise expressed, the chain to the extreme left of Fig. 2 is lower than the remaining two 60 chains; the central chain is slightly higher than the left chain, and the chain to the extreme right of Fig. 2 is higher than each of the first two chains. Obviously, therefore, when the material is placed on the chains, 65 said material will slant or slope toward one end of the tank. 70

In operation, the material to be pickled is placed in the loops 4^a of the chains 4, whereupon reciprocatory motion is applied to the shaft 6 and thereby to the gear wheels 5 through a suitable source of power (not shown). This reciprocation of said gear wheels causes the chains and the thereby carried material to move vertically and to be alternately dipped into the respective tanks. In other words, when the material of one tank is being lowered or dipped thereinto, the material of the other tank is being raised out of the tank, and vice versa. 80 85

It will be noted that the above described reciprocation of the gear wheels 5 causes alternate shortening and lengthening of the chains suspended in opposite tanks. Obviously, this change in the length of the section of chain over each tank imparts to the thereby carried tubes 9 a rolling motion so that their positions with respect to each other are changed with each reciprocation. This change in position permits the pickling fluid 90 95 100

to come in contact with the entire surface of the tubes, thus preventing a strip of the tube to remain unpickled.

From the foregoing it will be seen that the chains 4 function in a dual manner, first, to provide supports or carriers for the material being pickled and, at the same time, by virtue of the gear wheels 5 to effect movement of the material into and out of the bath.

What is claimed is—

- 10 1. In a pickling apparatus, a pair of tanks arranged in side-by-side spaced relation, a series of vertical columns on the outer side of each tank and a like series of vertical columns in the space between the tanks, the columns of the series being in register transversely of the tanks, a longitudinal reciprocal shaft journaled on the central series of columns, a series of gear wheels on the shaft, and a series of chains connected at their ends to the outer series of columns and having their central portions trained over the gear wheels, said chains being of such length that they form loops for the respective tanks between the gear wheels and the respective ends of the chains which loops constitute carriers for the material to be pickled, said chains further having their loops arranged in stepped relation so as to hold the material at an incline to the horizontal.
- 15 2. In a pickling apparatus, a pair of tanks arranged in spaced relation, a series of vertical columns on the outer side of each tank, and a like series of vertical columns in the space between the tanks, the columns of the series being in register transversely of the tanks, a longitudinal reciprocal shaft journaled on the central series of columns, a series of gear wheels on the shaft, and a series of chains connected at their ends to the outer series of columns and having their central portions trained over the gear wheels, said chains being of such length that they form loops for the respective tanks between the gear wheels and the respective ends of the chains, said loops constituting supports for the material to be pickled.
- 20 3. In a pickling apparatus, a pair of tanks arranged in spaced relation, a series of reciprocal gear wheels arranged between and above the level of said tanks, chains extending transversely of the tanks and having their central portions trained over said gear wheels, and means to secure the ends of the chains, said chains being of such length that they form loops for the respective tanks between the gear wheels and the respective ends of the chains, said loops constituting carriers for the material to be pickled.
- 25 4. In a pickling apparatus, a pair of tanks arranged in spaced relation, a series of flexible elements extending transversely of the tanks, means in register with the space between the tanks to engage and support central portions of the elements, means to sup-

port the ends of the elements for forming in the latter over the respective tanks loops adapted for the reception of articles to be pickled, and means to reciprocate said central supporting means for causing the loops alternately to move into and out of the tanks.

5. In a pickling apparatus, a pair of tanks arranged in spaced relation, a series of flexible elements extending transversely of the tanks, means whereby are formed article carrying loops in the elements for the respective tanks, and means to move said elements whereby to shorten one of the loops thereof and simultaneously lengthen the other loop thereby to move the articles into and out of the tanks.

6. In a pickling apparatus, a pair of tanks arranged in spaced relation, a plurality of flexible elements extending transversely over the tanks, rotary means arranged in underlying supporting relation to intermediate portions of said elements whereby are formed in the latter catenary carrying loops, said means being operable to increase and decrease alternately the lengths of said loops for moving thereby carried articles into and out of the tanks.

7. In combination with companion pickling baths, chains disposed transversely over said baths, means supporting the ends of said chains in fixed positions, rotary supporting means for said chains located between said baths whereby are formed in said chains catenary loops, said means being operable to lengthen and shorten said loops alternately for effecting alternate lowering and raising of thereby carried articles with respect to said baths.

In testimony whereof, I affix my signature.

STEPHEN L. WILLIAMS.
